(57) **CLAIM**

The ornamental design for the automobile wheel, as shown and described.

DESCRIPTION

FIG. 1 is a plan view taken from the front of the automobile wheel, showing my new design, the rear view, the right-side view, the left-side view, the top view and the bottom view are non-essential to my new design; and,

FIG. 2 is a perspective view thereof.

1 Claim, 2 Drawing Sheets

FIG. 1

FIG. 2
